UNITED STATES PATENT OFFICE.

HARRY C. FOSTER, OF CONNERSVILLE, INDIANA, ASSIGNOR, BY DIRECT AND MESNE ASSIGNMENTS, OF ONE-HALF TO GENERAL MOTORS CORPORATION, OF DETROIT, MICHIGAN, A CORPORATION OF DELAWARE, AND ONE-HALF TO INDIANA LAMP CORPORATION, OF CONNERSVILLE, INDIANA, A CORPORATION OF DELAWARE.

LAMP CONSTRUCTION.

Application filed August 14, 1924. Serial No. 732,030.

This invention relates to a lamp structure, and more particularly the means for securing the door or closure to the casing of the lamp.

5 There has been a problem in lamp structures to provide a suitable door fastening means which may be made at a minimum cost to secure the door in place under sufficient spring tension, whereby it will resiliently bear against the packing ring for preventing dust and moisture from entering, and permit the same to be readily removable. The usual hinge and clasp structure has been found to be too expensive and the 10 type now commonly used wherein the annular door rim or closure is rotated into locking position, while permitting production at low cost, is very difficult for the user to remove when necessary. For these reasons 15 the present structures are not satisfactory.

The main feature of this invention resides in the construction of the securing means for the door rim wherein it will overcome the difficulties above noted and at the 20 same time have the advantages. The invention consists in providing spring members of appreciable strength and spring tension over which the door rim may be engaged at the top for permitting said door rim to be 25 drawn against the casing at the bottom, overcoming the tension of said members and be secured at the bottom in position.

By reason of this invention there is no 30 expensive hinging of the door, while at the same time the door may be released and opened in substantially the same manner as though it were hinged. Furthermore, the 35 spring members will maintain the door under spring tension and contact with the lens 40 and sealing ring in the usual manner.

The full nature of the invention will be understood from the accompanying drawings and the following description and claims:

45 In the drawings, Figure 1 is a front elevation of a lamp embodying this invention;

Figure 2 is a central vertical cross section taken on the line 2—2 of Figure 1;

Figure 3 is a view taken in the direction 50 indicated by the line 3—3 of Figure 1;

Figure 4 is a section taken on the line 4—4 of Figure 1; and

Figure 5 is a modified form showing an-

other means for securing the door in closed position.

In the drawings there is shown the usual door or closure rim 10 and lens 11. The rim 10 is adapted to be mounted upon the lamp casing 12 which contains the usual reflector 13, there being a packing ring 14 of 60 the usual cord type positioned between an annular recess in the forward part of the reflector and the rear surface of the lens 11. Secured within the casing 12 there are inwardly extending flanges or brackets 15 65 against which a portion of the reflector abuts for maintaining it in position at the front of the casing.

The forward peripheral edge of the casing 12 is turned inwardly for making a bead 70 16 in which are nested the ends of a spring member 17. The spring member, as shown herein, is formed of spring wire and is provided with two arms 18 which extend rearwardly from the forward edge of the casing 75 and terminate in an upwardly projecting U-shape portion 19, said portion 19 projecting through a U-shape slot 20 cut in the periphery of the casing adjacent the forward edge thereof. The formation of the 80 U-shape slot 20 is such that it leaves a tongue 21 which will prevent the spring from dropping out of place and maintain the U-shape portion 19 in position above the outer surface of the casing. As shown 85 herein there is provided one of said spring members on each side of the vertical plane through the lamp, as illustrated in Figure 1.

The lower side of the casing, as shown 90 in Figure 4, has a portion stamped outwardly to provide a seat 22 for a spiral spring 23 which surrounds a latching rod or plunger 24 extending through said seat. The rear end of the rod is shown provided 95 with a washer 25 and a cotter pin for holding the spring in place, and the forward end thereof is provided with a latch or hook member 26 and finger piece or handle 27. The latch member 26 is adapted to hook over a latch bar 28 secured to the underside of 100 the door rim 10.

As shown in Figure 5, the lower portion 105 of the door rim is secured in place by means of a screw bolt 29, which extends through an ear 30 secured to the door rim, and screws 31 into a spring pressed member 32. The

spring pressed member 31 comprises a metal strength and tension which will act in a member bent at right angles having one portion extending through a small slot 32 in the plane perpendicular to the plane of the door 112, while the other end extends so that the door will be pulled directly through a suitable opening in the flange 116 of said casing. Said member has a stamped 70 portion to provide an ear 33 which will limit its rearward movement by engagement with the flange 116 of the casing, and is provided with a spiral spring 123 mounted thereon which abuts against the inner side of said flange at one end and against extended 75 portions 34 on the spring pressed member. It will be obvious that as the screw 29 is screwed into the member 31, it will cause 80 said member to slide in the slot 32 and draw it toward the door, compressing the spring 123, which in turn will exert a spring tension under which the door and casing will be drawn together.

The normal positions of the spring members 17 are such that the U-shape portions thereof are resiliently pressed against the rear ends of the U-shape slot 20, through 85 which they extend. When it is desired to mount the door rim upon the casing, it being assumed that the lens 11 is supported in the usual manner, either upon the door rim or upon the reflector, the upper portion 90 of the rim is first placed over the front edge of the casing so that the rear edge of said rim engages just behind the U-shape portions 19 of said spring members. The lower portion of the door rim is then brought 95 downwardly and over the lower portion of the casing, such movement causing the rim to engage the spring members and force them forwardly, with the upper portion of the sealing ring 14 and adjacent reflector 100 as a fulcrum. When the rim has been pulled down so as to embrace the lower portion of the casing as well as the upper portion, the latch member is pulled outwardly against 105 the pressure of the spring 23 and caused to engage the latching bar 28. The spring members 17 and the spring 23 will thereby cause the door to be drawn tightly in place 110 against the sealing ring 14 under spring tension.

If it is desired to use the locking means shown in Figure 5, the same effect may be had by tightly screwing up the screw bolt 29, pressure being exerted against the spring 123 thereby. It is obvious that in removing 115 the door, the release of the latch 26 or the screw bolt 29 will permit the door rim to be pulled outwardly, after which it may be lifted upwardly and out of engagement with the spring members.

From the foregoing it will be observed 120 that the two principal features of the invention reside in the simple structure of the device which will readily permit production at a minimum cost, while at the same time providing spring members of appreciable

70 strength and tension which will act in a plane perpendicular to the plane of the door so that the door will be pulled directly against the casing under the maximum tension of the spring members.

I claim:

1. In a lamp structure, the combination 75 with a casing having a slot in the periphery thereof and a closure therefor, of means for securing said closure in position thereon, comprising a spring member having a pair of arms seated within and against the forward edge of said casing and a central portion extending through said slot so as to provide a resilient projection extending outwardly from said casing in position to be engaged by said closure and forced forward under spring tension upon said closure being positioned upon the casing, a spring pressed member movable at right angles to the 80 closure on the opposite side of said casing, and means for detachably connecting the member to the adjacent portion of said closure.

2. In a lamp structure, the combination 90 with a casing having a slot in the periphery thereof and a closure therefor, of means for securing said closure in position thereon, comprising a spring member having spring- 95 arms, the ends of which are held in engagement with said casing, the central portion of said spring member being formed U-shaped and projecting outwardly from said casing through said slot and capable of being yieldingly compressed toward the front 100 of said casing, the projecting portion of said spring being so positioned as to be capable of being engaged by said closure rim and normally preventing the opposite side of said closure rim from embracing said casing, 105 and a latching member mounted on the opposite side of said casing from said spring member in position to engage said closure rim when forced into embracing position on said casing and maintaining the same there- 110 on against the tension of said spring member.

3. In a device of the character described, 115 a lamp casing and a closure having their rims overlapping, a reflector in the lamp casing, a flange projecting inwardly at the rim of the lamp casing and having an opening therein at one side of the casing, a yieldable and detachable connection between the closure and lamp casing at the other 120 side thereof, an angular plate having an arm slidably in said opening and the other arm projecting through the lamp casing, a spring interposed between the flange and the plate, and a member carried by the closure 125 for detachable connection with the projecting arm; substantially as described.

4. In a device of the character described, 130 a lamp casing and a closure having their rims overlapping, a reflector in the lamp cas- 135

ing, a flange projecting inwardly at the rim of the lamp casing and having an opening therein at one side of the casing, a yieldable and detachable connection between the closure and casing at the other side thereof, a 5 plate slidable through said opening and having a projection extending outside the casing, a spring interposed between said flange and the plate, and a detachable connection between the projection and the closure; substantially as described.

5. In a device of the character described, a lamp casing and a closure having their rims overlapping, a reflector in the lamp casing, a flange projecting inwardly at the rim of the lamp casing and having an opening therein at one side of the casing, a yieldable and detachable connection between the closure and casing at the other side thereof, a 10 plate slidable through said opening and having a threaded projection outside the casing, a spring interposed between said flange and the plate, and a screw rotatably carried by the closure and threaded in said projection; substantially as described.

6. In a device of the character described, a lamp casing member and a closure member having their rims overlapping, a reflector in the lamp casing, a yieldable and detachable 15 connection between the closure member and lamp casing member at one side thereof, a

spring pressed plate carried by one of said members at the other side thereof, and a screw rotatably carried by the other member and threaded in said plate; substantially as described.

7. In a device of the character described, a lamp casing and a glass holding casing having their rims overlapping one another, a reflector in the lamp casing, a detachable 20 connection between the two casings at one side thereof, a member slidable through one of the casings at the other side thereof and having one end exposed on the outside of the lamp assembly, a detachable connection between said end of the member and the other of said casings, and a spring for yieldably pressing the member towards its casing.

8. In a device of the character described, a lamp casing, a reflector mounted therein, a 25 glass holding casing having its rim enclosing the rim of the lamp casing, a yieldable detachable connection between the two casings at one side thereof, and a spring pressed member slidable in the lamp casing and having one end exposed on the exterior thereof and a detachable connection between said end of the member and said glass holding casing at the other side thereof.

In testimony whereof I affix my signature.

HARRY C. FOSTER.
